DISTILLATION METHOD AND APPARATUS

Kindred L. Storrs, Salt Lake City, Utah

Application July 19, 1946, Serial No. 684,720

7 Claims. (Cl. 202—28)

1

This invention relates to the separation of volatile constituents from distillable material, such as coal, by heating the same in a retort and conducting the evolved vapors to condensing means.

During the progress of the material through the retort, different volatile constituents are progressively and continuously released from the material and vaporized in different temperature ranges or heat zones, and the different vapors thus evolved are separately and continuously conducted from the respective heat zones to separate condensing means. In this way, substantially pure different vaporized constituents or fractions are separately evolved and collected, so that subsequent fractionation of the condensates is made unnecessary or minimized, depending upon the degree of refining of fractionation desired.

All grades or kinds of any particular type of material do not have the same constituents, nor are the respective constituents always released within the same temperature ranges. It is thus apparent that, in order to properly treat a particular kind or grade of material according to the method disclosed in my aforesaid pending application, it is necessary to first determine the constituents of that particular material and the particular temperature range in which each constituent is released or evolved, whereby the apparatus used may be correctly regulated to suit the material.

The primary object of the present invention, therefore, is to provide a practical method of and apparatus for treating any particular kind of distillable material to recover the constituents thereof and to determine the particular heat range in which each constituent of such material is released.

A further object is to provide a method and apparatus of the above kind whereby the treating operation may be easily and quickly carried out in a reliable manner.

More specific objects and features of the invention will become apparent from the following description when considered in connection with the accompanying drawings, in which:

Figure 1 is a fragmentary view, partly in side elevation and partly in section, showing a retort constructed in accordance with the present invention and forming part of an apparatus suitable for carrying out the present method;

Figure 2 is a view partly in elevation and partly in section on line 2—2 of Figure 1;

Figure 3 is a fragmentary perspective view

2

showing the means for collection and withdrawal of the evolved vapors from the hood of the retort of Figures 1 and 2.

Referring in detail to the drawings, the illustrated apparatus includes a suitable supporting frame 5 having a top 6 in the form of a slab of refractory material. Mounted on the frame above the slab 6 and by suitable means 7 is an endless trough 8 containing fluent material 9 and provided with a refractory lining and bottom facing 10. A further slab 11 of refractory material is mounted on the frame above and in spaced relation to the slab 6 and spaced from and within the confines of trough 8, by suitable means 12. Mounted on the slab 11 are electrical heating elements 13 supplied with current by use of an attachment cord 14. Mounted within the confines of trough 8 above the slab 11 and heating elements 13 is a vertically reciprocable vibrating pan 15 adapted to receive the material to be treated or analyzed. The pan 15 has a rim 16 which is provided on its outer edge with a depending flange 17 that extends into the trough 8 below the level of the fluent material 9. Mounted on the trough 8 by suitable means 18 is a hood 19 having an outer vertical wall 20 that surrounds the flange 17 of pan 15 and depends within the trough 8 beneath the level of the fluent material 9. Thus, a fluid seal is provided which prevents escape of gases from the retort between the pan 15 and hood 19 and permits the vertical reciprocation of said pan relative to said hood. The hood 19 has a suitable opening to facilitate introduction of the distillable material into pan 15, which opening is closed by a lid or gate 21.

The frame 5 has transversely disposed aligned bearings 22 directly beneath slab 6, and a horizontal rock shaft 23 is journaled in and projects outwardly of these bearings. Rigid with and rising from each projecting end of shaft 23 are spaced supports 24 having aligned top bearings 25 in which a cam shaft 26 is journaled. A cam disk 27 is secured on each shaft 26 between the adjacent bearings 25. Mounted for vertical movement between the retort and the slab 6 is a transverse horizontal rod 28 whose ends are engaged by the cams 27, and which has upstanding supports 29 rigid therewith and fixed to opposite sides of the pan 15. An adjusting screw 30 is slidable through each end of the rock shaft 23 and adjustably threaded into the adjacent end of rod 28. Adjustable on each screw 30 above the shaft 23 is an abutment washer 31. A helical compression spring 32 is disposed on each screw 30 between the shaft 23 and the adjacent washer 31.

and these springs act to yieldingly raise the rod 28 and keep it against the cams 27. Journalized in the lower portion of frame 5 is a transverse horizontal shaft 33 having its ends operatively connected by chain gearings 34 with the outer ends of cam shafts 26. Mounted within the frame 5 directly above shaft 33 is a motor 35 operatively connected to shaft 33 by gearing 36 and supplied with current by use of an attachment cord 36'. It will be apparent that motor 35 may drive the cams 27 to intermittently depress the rod 28 and then allow it to be raised by the springs 32. In this way, pan 15 is rapidly vibrated in a vertical direction so as to correspondingly vibrate the material being treated relative to the pan, and to thereby uniformly heat and rapidly distill the material.

Merely vibrating a mass of finely divided material in some fashion to bring about a condition which has frequently been described as "fluidized," is old and well known. However, there is a wide range of difference in the character of the vibrations when it is desired to attain specific results. The system of vibration involved in the method of the invention as accomplished by the mechanism illustrated and described in the present case is particularly effective to accomplish applicant's unique purpose. This purpose is to cause a mass of finely divided material particles to be so thoroughly disseminated that as far as possible each individual particle shall be effectually exposed to the processing conditions.

The vibratory action of the present mechanism is explained as follows:

The cam shaft 26 is mounted in bearings that are axially fixed center to center with reference to a stationary shaft 23. Seated on the shaft 23 are compression springs 32 and resting on the springs is a vibratory system consisting of a transverse rod 28 having fixed upstanding supports 29 upon which latter is fixed a pan 15 that is designed to contain the finely divided material for processing. The rod 28 does not rest directly on the springs but is supported on adjusting screws 30 which are threaded in the rod 28. Screws 30 pass freely through the springs 32 and through the shaft 23. Also, the screws 30 are provided with abutment washers that bear on the top of the springs and react against lock nuts threaded on the screws. Fixed on the cam shafts 26 are cam disks 27 the mutually reactive stress of which against springs 32 is taken up by the supports 24 which hold the centers of shafts 23 and 26 fixed relatively to each other.

Each complete rotation of the cam disks results in a cycle of motion consisting of two substantially vertical strokes, one down and the other up. The downstroke is exerted mechanically by the cam disks, and the upstroke by the potential energy stored in the springs during the downstroke. The peculiar nature of the strokes, presently described, characterizes an inventive feature. For example, in Figs. 1 and 2, the rotation of cam disks 27 may be regarded as occurring in cycles repeated indefinitely. A cycle may start when the low part of the cam is in contact with rod 28. Rotation of the cam disks until the high part of the disks contact rod 28 defines a downward stroke, and as aforesaid, stores potential energy in springs 32.

In the downstroke the energy consists of the mechanical input from the cams, plus the acceleration of gravity acting upon the load of vibratory parts. When the bottom of the stroke is reached, the momentum of the descending load

may carry the rod 28 somewhat lower than the peripheral point of the cams for the reason that the energy stored in the springs for the upstroke cannot be brought into action sufficiently fast to allow the rod 28 to closely follow the periphery of the cams. Thus, there is a small interval of time during which the fast-moving periphery is free of contact with rod 28, but this freedom continues only until the potential energy stored in the springs asserts itself and causes the rod 28 to be returned to contact with each cam periphery and to strike the same with a sharp hammer impact. This impact jolts the bottom of the pan 15 and shoots the particles upwardly into the desired cloudlike dispersion which brings about the rapid and thorough absorption of heat by the material particles.

A small interval of time at the bottom of a downstroke, where the spring tension is free of cam influence, is not dependent on the momentum of the descending load, but occurs in a degree because the slope of the cam periphery away from its high point, as well as the angular velocity of the cam, determines the point where contact is resumed. Thus, the intensity of the impact that sends the material particles into a shower and the nature of that shower can be nicely determined by recognizing the shape of the cam curve, its angular velocity and the tension of the spring as chief contributing factors to the desired end.

The vibrations produced by the apparatus of the invention are characterized by the sharp hammer-like jolts imparted to the processing pan.

After the desired end temperature has been reached and the treatment has been completed, the pan 15 may be tilted so as to cause the residue to flow from the latter by gravity. At the front, the pan 15 has a depending outlet spout 37 that extends through the slab 6 and into a fluid seal receptacle 38 removably supported on the underside of said slab. A gate valve 39 having a suitable opening means 40 controls flow of the material to the spout 37. The means to tilt the pan 15 may consist of an adjusting screw 41 threaded through a bracket 42 fixed to the frame 5, said screw 41 having a universal connection 43 with a stem 44 secured to an ear 45 rigid with the lower front portion of one of the supports 24. By adjusting the screw 41, the shaft 23 may be rocked so as to move all parts carried thereby and to accordingly tilt the pan 15 forwardly or return it to a horizontal position. Suitable means 46 may be used to indicate the position of the pan 15.

The hood 19 has a plurality of top outlet pipes 47 and 48 for the evolved gases, each leading to and extending downwardly through the stopper 49 of a separate removable sampling condenser receptacle 50. Each of the pipes 47 and 48 may depend into a body of water provided in the associated receptacle 50 to the level indicated at 51. Outlet pipes 52 may extend upwardly through the stoppers 49 from points above the water level and connect to the inlet of the motor driven suction pump 53 whose outlet 54 may lead to desirably located condensers and reservoirs. Interposed in each of the pipes 47 and 48 between the hood 19 and receptacles 50 is a shut-off valve 55.

In practice, a desired quantity of the distillable material is introduced into the pan 15 through the opening of hood 19 closed by cover 21. The heating elements 13 may then be energized and motor 35 is placed in operation so as to cause the pan 15 to be rapidly vibrated in a vertical direction, the gate 38 being closed. The heating ele-

ments 13 supply a predetermined amount of heat which is not varied or regulated. As the pan 15 is vibrated vertically, the finely divided or fluent material being treated is given a similar vibration so as to repeatedly rise and fall at uniform intervals relative to the bottom heating surface of pan 15. In this way, the particles of material being heated have heat transferred from the bottom or heating surface of pan 15 thereto, in a rapid and uniform manner. As the operation continues, the temperature of the material gradually increases until the end point of a given temperature range is reached. One of the valves 55 is then opened and the pump 53 is thrown into operation so as to draw the evolved gases from the hood 19 into the associated condenser receptacle 50, some gases being drawn, through the associated pipe 52, inlet pipe 52', pump 53, and outlet pipe 54 for condensation and collection. The valve 55 which has been opened is then closed and the other valve 55 is opened, and the active condenser receptacle 50 is withdrawn from its stopper 49 so that the sample condensate therein may be obtained, an unused receptacle 50 being substituted for that which has been removed. When the other valve 55 is opened, the operation is continued so as to obtain, in the second receptacle 50, and in the same manner, a sample of the condensate of the vapor evolved during the next higher heating stage. This cycle of operation is continued through successive higher stages of heat until the end temperature of the entire method or operation is reached. By careful operation of and attention to the apparatus, it can thus be readily ascertained as to what vapors are evolved during each of the particular temperature ranges so that proper data may be obtained for progressive distillation of the same material according to the continuous method disclosed in my aforesaid pending application. Upon completion of the distillation operation, the heating elements 13 are rendered inoperative and the pan 15 is tilted by actuation of screw 41 so that the residue of the operation may be discharged from pan 15 through spout 37 upon opening gate 39 by actuation of the opening means 40 thereof. During the distilling process, the fluent seal of the residue collection receptacle 38 prevented escape of gases from the retort through outlet spout 37. By taking samples of the evolved vapors at relatively short intervals or temperature change, it can be readily ascertained what the end temperature for each range of temperature should be in continuously distilling the same material according to the method and with the type of apparatus disclosed in my above mentioned co-pending application, thereby enabling the operator of the latter apparatus to properly operate and regulate the same.

From the foregoing description, it will be seen that the present method contemplates withdrawing the volatile constituents as they are evolved from the material during the different and successively higher temperature ranges, the volatile constituent evolved during each temperature range being prevented from mixing with that evolved during the previous or succeeding temperature ranges. In this way, substantially pure fractions are obtained directly from the retort at different periods of time while the temperature of the material is being raised to the desired final end temperature.

Modifications, and changes in details of construction of the apparatus, are contemplated.

such as fall within the scope of the invention as claimed.

What I claim is:

1. The method of separating volatile constituents from a discrete distillable material, which comprises the step of vertically vibrating the material in cycles, each cycle consisting of a downstroke and an upstroke, the downstroke being characterized by mechanical actuation exerted against a yielding tension while the upstroke is characterized by being actuated wholly by the energy stored in the yielding tension during the downstroke, the said upstroke further being subject to the deceleration of gravity acting upon the vibrating mass subjecting said material to a predetermined degree of heat so as to raise the temperature of each particle of the material to the desired end temperature, thereby causing different volatile constituents of the material to be successively evolved during a plurality of increasing temperature ranges; and separately collecting the volatile constituents evolved at predetermined temperature ranges.
2. The method of separating volatile constituents from a discrete distillable material according to claim 1, wherein a sample of each of said volatile constituents is separately condensed as it is collected.
3. An apparatus for separating volatile constituents from a discrete distillable material, comprising a closed retort provided with a vertically reciprocative receptacle for the material, said receptacle having a bottom heating surface; vertically reciprocative means including a support for the vertically reciprocative receptacle; spring means disposed to exert upwardly directed force upon said support; rotatable cam means operative downwardly upon said support in opposition to the spring force; driving means operative to rapidly rotate the cam means so as to vertically vibrate said receptacle; means to heat said bottom surface to a predetermined end temperature; a suction device operative to separately draw from the retort the volatile constituents evolved during each of a plurality of temperature ranges; and means operative to condense and collect each volatile constituent in the order drawn off.
4. The construction defined in claim 3, wherein is included a bottom outlet for said receptacle, valve means for controlling passage of residue from the receptacle to said outlet, and means operative to tilt the receptacle so as to cause flow of the residue to the outlet after opening said valve means.
5. The construction defined in claim 3, wherein in the retort includes a stationary hood provided with outlets for the evolved volatile constituents; and a seal between said receptacle and the hood.
6. The construction defined in claim 3, wherein in the retort includes a stationary hood provided with outlets for the evolved volatile constituents; a seal between the receptacle and the hood; a shut-off valve in each outlet; and wherein the sample condensing and collecting means includes a removable receptacle interposed in each outlet beyond the associated shut-off valve.
7. A method of separating volatile constituents from a discrete distillable material comprising the step of vertically vibrating the material in cycles, each cycle including a mechanically actuated downward stroke exerted against an upwardly directed yielding tension and an upward stroke which is substantially free of the mechanical actuation, but is actuated by the en-

ergy stored in the yielding tension during the downward stroke; subjecting said material during vibration to a predetermined uniform degree of heat sufficient for rapidly and uniformly bringing each particle of the material to the desired end temperature which causes the material so vibrated and heated to rapidly release its volatile constituents.
